Primary Examiner — Ian Simmons*Assistant Examiner* — Dana L Sipos(74) *Attorney, Agent, or Firm* — Pearne & Gordon LLP**(57) CLAIM**

The ornamental design for a bottle, as shown and described.

DESCRIPTION

FIG. 1 is a top perspective view of a bottle showing my new design;

FIG. 2 is a front elevation view thereof;

FIG. 3 is a top plan view thereof;

FIG. 4 is a right side elevation view thereof;

FIG. 5 is a left side elevation view thereof; and,

FIG. 6 is a rear elevation view thereof.

The broken dot-dash line in FIG. 3 defines the bounds of the claim and forms no part thereof.
